In Sweden January 3, 1948

13 Claims. (Cl. 122—1)

1

Our invention relates to extended surface heat exchangers such as used in steam boilers and the like for effecting indirect heat transfer between two media having different surface conductances and contemplates a structure for this purpose which will be capable of withstanding continued subjection to gas temperatures higher than 1200 degrees centigrade. The invention is especially applicable to the convection surfaces of steam boilers. So utilized it effects as much as a ninety percent reduction in the amount of tubing required for the convection surfaces and reduces the space required by the convection surfaces to one-eighth that necessary in a La Mont type boiler, which is considered one of the most efficient boilers presently available.

Our invention also makes it possible to greatly increase the efficiency of boilers and furnaces now in service by the simple expedient of incorporating a relatively small unit constructed in accordance with this invention in the flue gas duct connecting the boiler with the stack; and by virtue of the small space they require, boiler units constructed in accordance with this invention are ideally suited to the utilization of otherwise wasted heat emanating from blast furnaces and other industrial heat sources.

By the same token the invention is especially important to marine boilers where its increased efficiency enables a higher steaming rate and consequently faster speeds, or conversely because of reduced fuel consumption and decreased weight, effects an increased cruising range.

Our invention also contemplates the improvement and reduction in overall size of oil pre-heaters and similar apparatus where condensing steam is frequently used as the heating medium, and where the designers of past apparatus for this purpose took no account of the difference in conductance values of oil and steam.

We have also found that the utilization of radiant heat, as in hot air furnaces, can be greatly improved by the application of this invention thereto.

Our invention recognizes the fact that by increasing the heat transfer surfaces exposed to the medium of lower surface conductance and proportioning and arranging them in accordance with certain formulae, the rate of heat transfer of the medium of lower surface conductance can be brought more nearly into balance with the rate of heat transfer of the medium of higher surface conductance.

2

Specifically our invention consists in the provision of extended surface in the form of rod-like heat transfer elements joined to the boiler fluid containing tubes or partition wall separating the two media and extending into and substantially across the zone containing the medium of lower surface conductance so as to be in direct heat transfer relation thereto while having indirect heat transfer relation via the wall with the medium of higher surface conductance. The objectives of the invention are achieved through proper proportioning and arrangement of these heat transfer elements.

It is recognized that numerous attempts have heretofore been made to improve heat exchange between two media through the provision of fins, rods and other elements carried by the tubes or other partition walls separating the media and extending into one or both of the media, but as far as we know there has never been a teaching of how through the use of extended surface the convection surfaces of a steam boiler of the La Mont type, for instance, could be reduced to such an extent as to require only one-eighth the space heretofore necessary. To the best of our knowledge the selection of the shape, proportions and geometrical arrangement of extended heat transfer surfaces has always proceeded upon a "cut and try" basis, and such empirical experimentation has been very costly. In contrast our invention is predicated upon the discovery of certain demonstrated scientific facts concerning these factors and their significance, and as will appear more fully hereinafter, provides adequate instructions for the design of apparatus capable of achieving the purposes of this invention.

In summation the objectives of our invention are:

- 40 (1) To provide a more efficient indirect heat exchange between two media of different surface conductances;
- 45 (2) To provide heat exchange apparatus especially adapted for use as the convection surfaces of a steam boiler and by which the tubing required is reduced to one-tenth that heretofore necessary and the overall space required for the convection surfaces is reduced to approximately one-eighth that heretofore necessary;
- 50 (3) To provide means for increasing the efficiency of boilers and furnaces now in service;
- (4) To reduce the size and increase the efficiency of oil preheaters;

(5) To improve the utilization of radiant heat.

With the above and other objects in view which will appear as the description proceeds, our invention resides in the novel apparatus substantially as hereinafter described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best modes so far devised for the practical application of the principles thereof, and in which:

Figure 1 is a view diagrammatically illustrating a La Mont type boiler having its convection surfaces constructed in accordance with our invention, the illustration of these surfaces, for the sake of clarity, being somewhat exaggerated and thus not truly in proportion with the rest of the apparatus;

Figure 2 is a diagrammatic illustration of a typical La Mont boiler showing how much of its total space requirements are devoted to the convection surfaces, and showing by comparison the vast reduction of this space effected by the present invention;

Figure 3 is a longitudinal sectional view upon an enlarged scale through the flue gas passage of the boiler shown in Figure 1 and illustrating a section of the convection surfaces;

Figure 4 is a cross sectional view through Figure 3 on the plane of the line 4—4;

Figure 5 is a detail sectional view upon a still larger scale through two tubes of the convection surfaces shown in Figure 3 with the heat transfer elements attached thereto;

Figure 6 is a cross sectional view through Figure 5 on the plane of the line 6—6 showing the arrangement of the heat transfer elements with respect to each other and the gas flow thereover;

Figure 7 is a view partially in side elevation and partially in longitudinal section illustrating the application of this invention to an existing boiler installation to utilize the ordinarily wasted heat of the exhaust flue gases and thereby increase the efficiency of the boiler;

Figure 8 is a cross sectional view through Figure 7 on the plane of the line 8—8;

Figure 9 is a graph showing the relative efficiency of the boiler to which we applied the apparatus of Figures 7 and 8, before and after such application;

Figure 10 is a graph explaining the symbol used herein to denote the conductivity efficiency of the individual heat transfer elements which collectively comprise the extended surface;

Figure 11 is a chart showing a set of curves we have plotted to facilitate determination of the maximum length of the individual heat transfer elements in accordance with our invention;

Figure 12 is a vertical sectional view through a hot air furnace illustrating the application of this invention to the improvement of the utilization of radiant heat;

Figure 13 is a view partially in side elevation and partially in longitudinal section illustrating the application of this invention to an oil pre-heater; and

Figure 14 is a cross sectional view through Figure 13 on the plane of the line 14—14.

Before specifically considering several embodiments of the invention illustrated in the accompanying drawings, it is essential that the term

"surface conductance" be fully understood. By this term is meant the ability of a medium to effect heat transfer between itself and a surface of a solid exposed thereto. It involves such considerations as the physical properties peculiar to the medium; the temperatures of the medium and the surfaces involved; the velocity of the medium if flowing or in motion; the shape and dimensions of the surface exposed to the medium; the disposition of the surface in the medium with respect to its direction of flow or motion; and its proximity to other surfaces or obstructions within the medium which would have an effect upon the manner in which the medium contacts the surface.

More specifically the term "surface conductance" as used herein (throughout the specification and claims) has the same meaning as the designation "alpha value" obtained by the following formulae and correction we have found necessary:

For the staggered arrangement of the heat transfer elements providing the extended surface as shown in Figure 6—

$$\alpha = \left[1.29 + \frac{0.424}{\left(\frac{S_t}{d} \right)^2} + 0.124 \times \frac{S_t}{d} \right] \sqrt{T} \times \frac{V_0^{0.41}}{d^{0.39}} \text{ k cal./m.}^2/\text{h.}^{\circ}\text{C.}$$

For a rank and file arrangement of the heat transfer elements, i. e. where the elements are arranged one behind the other in side-by-side rows or files—

$$\alpha = \left[1.59 - \frac{0.97 \times \left(\frac{S_t}{d} \right)^{1.5}}{\left(\frac{S_t}{d} \right)^4} \right] \sqrt{T} \times \frac{V_0^{0.41}}{d^{0.39}} \text{ k cal./m.}^2/\text{h.}^{\circ}\text{C.}$$

where

S_t is the center-to-center distance between adjacent heat transfer elements in meters and measured at right angles to the direction of gas flow

S_t is the center-to-center distance between adjacent heat transfer elements in meters and measured in the direction of gas flow

T is the absolute temperature of the gas = $t_g + 273^{\circ}$ C.

V_0 is the velocity of the gas in m./s. at 0° C.

d is the diameter of the heat transfer elements in meters

While these formulae have been obtained from Dr. Ing. Alfred Schack's book "Der Industrielle Wärmeubergang" (1940 edition), page 121, we have found that the values obtained thereby are too high by thirty percent (30%) for the practical application in apparatus of the kind contemplated by this invention.

Seventy percent (70%) of the values obtained by the application of the preceding formulae are correct. Hence, where the term "surface conductance" is used herein it should be understood that we mean the value obtained by the given formulae corrected by a thirty percent (30%) reduction.

It should also be specifically noted that for the conditions which normally obtain in a steam boiler the surface conductance of steam or water, i. e. the boiler fluid, is at least one hundred times greater than that of combustion gases; and that at 50 degrees C. and the same velocity the surface conductance of oil is only nine percent (9%) that of water.

From this it follows that no useful purpose is

achieved by merely increasing the surface area of a wall separating water and hot combustion gases for instance, equally at both sides of the wall, for by virtue of its greater surface conductance the rate of heat transfer which obtains between the water and the surface in contact therewith is far greater than the rate of heat transfer that can be obtained between the hot gases and the same wall.

It also follows that if the heat transfer surfaces in heat transfer relation with the hot gases are increased and those surfaces are properly proportioned and disposed with respect to the gas flow, it is possible to increase the rate of heat transfer between the gases and the surfaces exposed thereto to the extent that said rate begins to balance the maximum obtainable rate of heat transfer between the water and the inside of the tube containing it. A mere haphazard collection of prongs or fins on the outside of the tube, however, does not suffice.

It should also be understood that practical considerations—for instance the excessively high temperatures to which apparatus of this character is subjected, the need for cleaning off accumulations of soot and dirt from the surfaces, and the basic mechanical strength requirements—increase the difficulties which the problem presents.

Referring now particularly to the accompanying drawings and especially to Figures 1 to 6 inclusive, the numeral 5 designates the fire box or combustion zone of a La Mont type boiler the walls of which are lined with tubes 6 as is customary. Water is circulated through these tubes from a steam dome 7 by means of a pump 8. The combustion gases leave the fire box or combustion zone through a flue gas duct 9 which leads to the stack (not shown).

Within the flue gas duct 9 are the convection surfaces 10 of the boiler, comprising a steaming section, a superheater section, an economizer and an air heater as indicated in Figure 1. The manner in which the several sections of the convection surfaces are connected in the system follows conventional practice. Though mentioned hereinbefore it is desired to again point out that for the sake of clarity the illustration of the convection surfaces in Figure 1 is somewhat exaggerated. Actually they would occupy less space than that illustrated.

The saving in space which our invention effects in a La Mont type boiler is graphically shown in Figure 2. Here a typical La Mont type boiler is diagrammatically illustrated with that portion thereof containing the convection surfaces and air heater cross hatched. In accordance with existing practice the flue gas duct is shown extending down along the back wall 11 of the combustion zone, this arrangement having been considered most feasible from the standpoint of space saving.

With the application of the present invention to the La Mont type boiler the great reduction in the space necessary to house the convection surfaces permits the flue gas duct to extend directly up from the top of the combustion zone as shown in Figure 1.

As shown in Figures 3 to 6 inclusive the amount of tubing 12 employed for the convection surfaces is materially less than that heretofore necessary. Actually the reduction amounts to ninety percent (90%). This follows from the fact that the primary heat transfer surfaces are not the tube walls but instead consist of extended surface provided by heat transfer elements 13 suitably joined

to the tubes in intimate heat transfer relation thereto.

The elements 13 have a small cross section compared to their length. Specifically the cross sectional area of the elements should be between 3 and 50 mm.² and their cross sectional shape is preferably round though any other section may be used as long as the major transverse dimension does not exceed three times the minor transverse dimension. This assures desirable turbulent flow.

The minimum length of the elements, i. e. of their conductance paths, should be not less than ten times the square root of their cross section, or to be more exact, the minimum length of the conductance path (measured in mm. or any other suitable unit of measurement) shall not be less than ten times the square root of the number expressing the cross sectional area of the element (in mm.² or whatever other unit of measurement is employed to express the length of the path).

The optimum maximum length of the elements bears a definite relationship to the temperature to which the elements are subjected, the cross sectional area of the elements, the conductivity coefficient of the elements and the surface conductance of the gas, and can be determined with relative accuracy by means of the following formula in which the symbol η_g signifies the heat transfer efficiency of the elements:

$$\eta_g = \frac{1}{nl} \times \frac{e^{2nl} - 1}{e^{2nl} + 1} \text{ where } n = \sqrt{\frac{\alpha \times F}{\lambda \times f}}$$

and where

α =the surface conductance (alpha value) of the gas as determined by the appropriate formula with the 30% correction explained hereinbefore

λ =the conductance of the metal of which the elements are made

e =base natural logarithm (=2.718)

F =circumference of element in M

f =cross sectional area of element in M²

l =length of conductance path in M

In further explanation of the heat transfer efficiency η_g , reference is made to the diagram shown in Figure 10. From the diagram it will be seen that η_g represents the temperature difference between the gas temperature and the mean temperature of the element 13 divided by the temperature difference between the gas temperature and the wall temperature at the gas side of the tube. On this diagram the curve $a-b$ represents the temperature gradient along the length of the element and the two shaded areas above and below the curve $a-b$, being equal in area, establish the point of mean temperature along the curve $a-b$.

Since a full appreciation of the significance of the heat transfer efficiency η_g is essential to a clear appreciation of our invention further explanation thereof is warranted. Expressed in another way, this symbol signifies the relation between the heat quantity transmitted through an element in a practical apparatus in which the temperature of the element by necessity increases along the length thereof and towards its outer end, and the heat transmitted by the same element under comparable conditions if the temperature throughout the element was constant and equal to the temperature at the base of the element where it is attached to the wall of the tube. The latter condition is, of course, impossible to obtain in an actual apparatus; but this criterion of efficiency (η_g) can be effectively

used to establish the optimum maximum length of the elements.

The most convenient way of using this criterion is to set up a family of curves such as shown in Figure 11 by calculations employing the aforesaid formula. These curves may be plotted for any number of surface conductances, α values, for any given cross sectional area of the elements. In Figure 11 the calculations involved in plotting the curves were predicated upon the cross sectional area of an element of 3 mm. diameter and in these calculations the heat transfer efficiency was mathematically determined from the η_g formula for each assumed alpha value at assumed lengths of conductance paths. Thus for instance for the alpha value of 75 and a length of .01 meter the heat transfer efficiency is .989; for .02 meter the heat transfer efficiency is .963; for .03 meter it is .916; for .04 meter it is .863, etc.

If through the use of this η_g formula it is found that the efficiency of the conductivity of the elements is at least sixty percent (60%) of theoretically complete (100%) heat transfer the dimensional factors and thermal-conductivity of the elements are satisfactory for temperature below 600° C., but where temperatures exceed 600° C. this conductivity efficiency should be at least seventy-five percent (75%). In other words, with higher temperatures shorter elements must be used, but to obtain maximum efficiency for the apparatus the elements should be as long as conditions will permit.

In this connection it should be noted than an imaginary wall with no transfer losses whatsoever would provide complete heat transfer and one hundred percent (100%) efficiency of conductivity.

It should be understood that in the foregoing references to the length of the elements 13 we mean the length of the conductance path provided thereby to the nearest base surface. Where the elements are in the form of loops or rods projecting from the wall to which they are attached, the length of the conductance path is the distance measured along the axis of the element from its final point of contact with the base wall to the point farthest therefrom. Where the elements connect two tubes, as shown for instance in Figures 3, 4 and 5, the length of the conductance path is one-half the distance (measured along the axis of the element) between the points of final contact between the elements and tubes.

The elements 13 should be of metal having a high coefficient of thermal-conductivity, preferably at least 90 Kcal./hr./m.²/°C./m. Copper is ideal though other material such as aluminum, nickel, brass, zinc, steel and various alloys may be used.

The junction of each element 13 with its base surface, specifically the wall of the tube to which it is secured, should be at least as great as the cross sectional area of the element. The junctions may be effected by welding, brazing or any other way of securing a good heat transfer connection.

While the specific arrangement of the tubes and the heat transfer elements thereon may be varied, that shown in Figures 3 to 6 inclusive has proved especially satisfactory. As here shown each section of the convection surfaces consists of a plurality of banks or strata 14 of tubing with heat transfer elements mounted thereon and with the tubing arranged in serpentine fashion and all formed from one continuous length

of tubing. The serpentine coils comprising each bank are divided into three sets each of which has its own heat transfer elements 13 thereon. Each set of coils with its heat transfer elements arranged thereon, thus may be considered a heat absorbing "mat" 15 and collectively these mats present a heat absorbing screen extending fully across the flue gas duct.

The elements 13 of each mat are preferably one continuous length of wire of a size lying within the prescribed limits of 3 and 50 mm.² and chosen with respect to such considerations as necessary mechanical strength, gas temperatures and adequate provision for cleaning soot and dirt from the elements. In no event, however, should the cross sectional area of the elements exceed 50 mm.² since wires or rods larger than this do not possess sufficient advantage (in heat transfer) over the smaller diameter tubes used in boilers of the forced circulation type, as for instance, the La Mont.

We have found that the combined volume of all of the elements, i. e. the total volume of the extended surface, should be between 5% and 25% of the volume of the zone or duct in which they are located, and that the total extended surface area provided by the elements and exposed to the gases should be not less than 50 mm.² nor more than 200 mm.² per cubic meter of that portion of the zone or duct containing the elements.

Also, we have found that the total exposed area of the heat transfer elements should be not less than three (3) nor more than sixteen (16) 35 and preferably not less than five (5) nor more than ten (10) times as great as the projected area of the wall portion (exterior of tubes) adjacent to that part of the zone or duct containing the elements. It is to be understood that 40 the projected area in the case of a tube is the diameter of the tube times the length thereof, and that the projected area thus considered should encompass the junctions of all of the elements to the wall and extend beyond the outermost or border junctions a distance one-half the spacing between adjacent junctions since for this area the transmission of heat by all of the elements into the wall will be the same.

In the application of the heat transfer elements 50 13 to the tubes, the wire from which the elements are formed is wound about the legs of the tube coils in elongated loops and then one side of every other loop is indented or deformed towards the median plane containing the axes 55 of the tubes and over the tubes, and at the same time the remaining loops have their other sides similarly indented or deformed to bring about the staggered arrangement of the elements shown in Figure 5 and Figure 6, with all of the extended surface provided by the elements, of course, extending transversely or normal to the direction of gas flow. The extent of the indentations of the loop sides is such that the distance between the straight undeformed sides of the loops is equally divided by the indented portions.

To more clearly illustrate the application of our invention to a steam boiler, the essential dimensions and data for a typical installation are 70 set out below. The example applies to the convection surfaces of a La Mont type boiler but not necessarily the one shown in Figures 1, 3 and 4, and contemplates the staggered arrangement of heat transfer elements like those shown in Figures 3-6 inclusive. The important data and

dimensions of the installation chosen for illustration are as follows:

Volume of gas at 0° C.=4350 normal m.³/h.
Temperature of gas entering convection surfaces=1000° C.
Temperature of gas leaving convection surfaces=450° C.
Absolute mean temperature of the gas=

$$\frac{1000+450}{2}+273=998^{\circ}\text{C.}$$

Steam pressure=25 atm. gauge
Steam temperature (t_s)=225° C.
 V_0 (gas velocity) at 0° C.=2.1 m./sec.

The tubes are formed of standard steel boiler tubing and have an inside diameter of 12 mm. and an outside diameter of 16 mm. The size and amount of the tubing is determined with regard to the temperatures and heat release involved and must be such that the tubes at all times contain sufficient water to maintain desirable flow characteristics. The water should exceed the steam generated by as much as four to ten times (by weight). This ratio assures clean tubes and good results generally.

The individual heat transfer elements are of copper and have a diameter of 3 mm. Their center-to-center distance at right angles to the direction of gas flow (the S_0 value of the surface conductance formulae above) is 12 mm.

The surface conductance of the gas, using the appropriate formula given above (the first for staggered element arrangement) is

$$\alpha = \left[1.29 + \frac{0.424}{\left(\frac{6.3}{3}\right)^2} + 0.124 \times \frac{12}{3} \right] \sqrt{998} \times \frac{2.1^{0.61}}{0.003^{0.39}} = 161$$

70% of this is 113 kg. cal./m.²/°C./h.

The value 6.3 is the S_0 dimension of the formula and is obtained as follows: the diameter of the tube, 16 mm., plus one diameter of the elements, viz. 3 mm., provides a center-to-center distance of 19 mm. between the straight undeformed sides of the loops formed by the heat transfer elements. Indenting the opposite sides of the loops in the manner described divides this distance of 19 mm. by 3 which makes the S_0 distance 6.3 mm. The 998° C. is the absolute mean temperature of the gas as noted hereinbefore.

Using the family of curves shown in Figure 11 to determine the length of the elements, i. e. of the conductance paths afforded thereby, and an assumed heat transfer efficiency of 88% and an alpha value of 113 kg. cal./m.²/°C./h. it will be found that the length of the conductance paths provided by the looped elements 13 should be about 30 mm.

The accuracy with which the curve is read in the above determination of the length of the conductance paths can be checked and verified by the formula as follows:

$$\eta_s = \frac{1}{nl} \times \frac{e^{2nl} - 1}{e^{2nl} + 1} \text{ where } n = \sqrt{\frac{\alpha \times F}{\lambda \times f}}$$

$$n = \sqrt{\frac{113 \times 0.0094}{325 \times 7.1 \times 10^{-6}}} = 21.5$$

$$\eta_s = \frac{1}{21.5 \times 0.003} \times \frac{2.718^{2 \times 21.5 \times 0.003} - 1}{2.718^{2 \times 21.5 \times 0.003} + 1} = 0.88$$

Since the conductance paths provided by the looped ends of the elements are of the same length as the paths provided by the straight portions of the elements from each tube to the mid-

point of the loop, the over-all outside dimension of the elongated loops formed by the elements is approximately 115 mm.

The optimum length of the conductance paths, of course, also determines the center-to-center distance between the tubes which in the illustration given comes to 60 mm.

By computing the surface area of the looped elements and deducting eleven percent (11%) for the approximate area thereof encompassed by the welded junctions of the loops to the tubes it will be seen that an extended heating surface of 117 m.² per m.³ volume is obtained. This is well within the range heretofore prescribed, viz. 50 m.² to 200 m.² per m.³

The cross sectional dimensions of the flue duct are 600 x 1600 mm. and the mats, each 1600 mm. long, are arranged flatwise edge-to-edge so as to dispose five mats in each bank across the flue duct. Ten banks of mats comprise the total convection surfaces with the vertical center-to-center distance between adjacent banks 25.2 mm. The total height of the entire mat assembly is thus 9 x 25.2 + 22 mm. (one mat thickness)=249 mm.

The volume of the gas pass or duct required for the entire mat assembly (the total heating surface) is $0.6 \times 1.6 \times 0.249 = 0.239$ m.³.

The area of the heating surface contained within this volume is $117 \times 0.239 = 27.9$ m.².

The dimensions and data given thus far apply to the gas side of the wall separating the two media, i. e., the outside of the tubes. For the water side the following information is given.

The effective heating surface (inside of tubing in contact with water) is 6.0 m.². Inasmuch as the tubes contain a water-steam emulsion the surface conductance is at least 10,000 Kcal./m.²/°C./h.

The mean temperature drop between the water-steam emulsion and the tube wall is 15.3° C., determined as follows:

$$4350 (1000 \times 0.364 - 450 \times 0.340) = 916,000 \text{ Kcal./h.}$$

where 0.364 is the average specific heat of the gas between 0° and 1000° C., and 0.340 is the average specific heat of the gas between 0° and 450° C.

$$\frac{916,000}{10,000 \times 6.0} = 15.3^{\circ}\text{C.}$$

The mean temperature drop in the tube wall=

$$916,000 \times \frac{0.002}{45} \times \frac{1}{6.0} = 6.8^{\circ}\text{C.}$$

The total mean temperature drop through the tube wall is thus 22.1° C. The temperature difference between the gas and the water-steam emulsion at the point the gas enters the convection surfaces is

$$\begin{aligned} & 1000^{\circ}\text{C. (gas temp. at hot end)} \\ & - 225^{\circ}\text{C. (steam temperature)} \\ & \hline 775^{\circ}\text{C.} \end{aligned}$$

The temperature difference between the gas and the water-steam emulsion at the point the gas leaves the convection surfaces is

$$\begin{aligned} & 450^{\circ}\text{C. (gas temp. at cool end)} \\ & - 225^{\circ}\text{C. (steam temperature)} \\ & \hline 225^{\circ}\text{C.} \end{aligned}$$

The mean temperature difference between the gas and water-steam emulsion thus is

$$\frac{775+225}{2} = 500^{\circ}\text{C.}$$

The corresponding difference at the point where

11

the gas enters the convection surfaces consequently will be

$$\frac{775}{500} \times 22.1 = 34^\circ \text{ C.}$$

and for the point where the gas leaves the convection surfaces it will be

$$\frac{225}{500} \times 22.1 = 10^\circ \text{ C.}$$

The wall temperature of the tube on the gas side at the point of gas entry into the convection surfaces is thus

$$225 + 34 = 259^\circ \text{ C.}$$

and at the point the gas leaves the convection surfaces

$$225 + 10 = 235^\circ \text{ C.}$$

The temperature difference between the gas and the elements at the hot gas inlet end of the convection surfaces is:

$$0.88 (1000 - 259) = 652^\circ \text{ C.}$$

and at the cooler discharge end

$$0.88 (450 - 235) = 189^\circ \text{ C.}$$

0.88 being η (the heat transfer efficiency).

The logarithmic mean temperature difference between the gas and the elements = 374° C. , which was calculated as follows:

$$\frac{652 - 189}{\log \frac{652}{189}} = \frac{463}{3.45} = 374^\circ \text{ C.}$$

To check the required heating surface, i. e., effective surface of heat transfer elements

$$\frac{916,000}{113 \times 374} = 21.7 \text{ m}^2.$$

which is less than used, viz. 27.9 m^2 .

In the illustration given it will be seen that the rate of heat transfer at the gas side (outside of tubes) has substantially approached the maximum obtainable rate of heat transfer on the water side (inside of tubes), this being evidenced by a comparison of the products of the surface conductance times the heat transfer area at opposite sides of the wall.

$$10,000 \times 6.0 = 60,000$$

$$113 \times 27.9 = 3,153$$

$$\frac{60,000}{3,153} = 19$$

The product of the surface conductance on the water side times the heating area is thus 19 times as great as the product on the gas side.

The significance of this conclusion will be seen when it is appreciated that if tubes alone were used, the surface conductance (alpha value) on the gas side would be decreased to about 67. This value, multiplied by the total surface area of the exterior of the tubes would result in a product of 535.5; and this compared to the product 60,000 would make the product on the water side 112 times greater than on the gas side.

In Figures 7 and 8 we have illustrated the application of this invention to an installation designed to recover ordinarily lost heat and thus improve the efficiency of an existing boiler which has been merely indicated and designated by the numeral 16. In this embodiment of the invention a unit 17 is connected between the flue gas outlet of the boiler and the stack 18. To enable such connection a T-shaped duct 19 was sub-

12

stituted for the direct connection between the boiler and the stack and an elbow section 20 was connected with the stack upstream.

The unit 17 is mounted between the duct sections 19 and 20 and comprises a flue gas passage 21 defined by two spaced water ducts 22 connected by two side plates 23. The water ducts 22 have an inlet header 24 connected to the upper ends thereof as at 25 and a similar outlet header (not shown) connected to the lower ends thereof as at 26. Within the flue gas passage 21 and extending between the inside walls 27 of the water ducts are heat transfer elements 28. These elements extend transversely to the direction of the gas flow and consist of lengths of copper wire of a diameter ranging between two and eight millimeters wound about collector rods 29.

The elements are secured to the rods 29 and to the inside walls 27 of the water ducts in good heat transfer relation thereto by welding, brazing, or otherwise, and the combined volume of the heat transfer elements 28 constitutes between five and twenty-five percent (5% and 25%) of the total volume of the flue gas passage 21. Experience has shown that this ratio is best suited to the achievement of the purposes of our invention taking into account all the factors such as accessibility for cleaning, maintenance and adequate gas flow, etc., which govern the amount 30 of heating elements that can be incorporated in a gas pass of given volume. Obviously the ratio should be as high as possible consistent with these factors.

The combined area of the elements exposed 35 to the gases is between three and sixteen times greater than the projected area of the walls 27 served by the elements, and preferably between five and ten times said projected area of the walls 27, this ratio being determined by the same 40 considerations involved in the selection of the aforesaid volumetric ratio.

To enable access to the heat transfer elements for cleaning, removable covers 31 are provided in the T and elbow duct sections 19 and 20 respectively. With the removal of these covers cleaning brushes, soot blowers or other suitable means may be employed to clean the accumulated soot and dirt from the elements 28.

Valves 32 are also preferably provided in the 50 outlets of the duct sections 19 and 20 by which the gas flow may be directed through the unit 17 or past it.

The results of tests conducted with a unit such as that disclosed in Figures 7 and 8 and extending 55 over a period of four months are plotted on the graph of Figure 9. From this graph it is apparent that without the unit of this invention the boiler to which it was attached showed a decreasing efficiency with increasing load, as represented by curve A. At the prevailing load for the four month period, indicated by the line B-B, this boiler was less than fifty percent (50%) efficient. During the same period and under identical conditions the efficiency of the same boiler 60 with the unit 17 attached thereto and operating was eighty percent (80%) as shown by curve C. This represents a fuel saving of forty percent (40%) under the prevailing conditions, as indicated by curve D, the curves C and D, of course, being independent of one another.

The average temperature of the flue gases entering the unit 17 during these tests was 450° C. while the temperature of gases leaving the unit and entering the chimney or stack was only 75 120° C.

As illustrated in Figure 12 the invention also improves the utilization of radiant heat as in a furnace. To this end the invention takes cognizance of the relatively great differential in surface conductance which obtains at opposite sides of a wall subjected at one side to the direct radiant heat rays emanating from the bed of burning fuel and at the other side to the air to be heated and in motion thereover.

In this embodiment of the invention a metal wall 33 is subjected to direct radiant heat rays emanating from a combustion zone 34. This wall coacts with an outer shell 35 and suitable end walls 36 (only one of which is indicated) to define an air duct or passage into which air to be heated is fed through an inlet 37 and from which hot air is discharged through an outlet 38. Preferably the shell 35 is equipped with an insulating jacket 39.

Within the air passage thus defined are rows of serpentine heat transfer elements 40 attached to the wall 33 in heat transfer relation thereto by welding, brazing or otherwise but having no contact with the outer shell 35.

Through proper proportioning and spacing of these heat transfer elements 40 the rate of heat transfer between the air being heated and the heating surfaces can be increased to an extent which approaches the maximum obtainable rate of heat transfer between the radiant heat rays and the wall 33. In this case the heat rays are the medium of high surface conductance while the air to be heated is the medium of low surface conductance. Attention is directed to the fact that the situation which obtains here is not the same as where the wall separates media of substantially the same surface conductance.

Figures 13 and 14 illustrate the application of our invention to an oil preheater. In this case the oil is the medium of low surface conductance, for the heating medium is condensing steam which enters the apparatus through a central duct 41, flows along the length thereof to debouch into an annular passage 42 defined by the wall of the duct 41 and a tube 43. Both ends of this tube are closed and a discharge 44 leads from its exposed end portion through which the condensate leaves the apparatus.

The heating unit, consisting of the duct 41 and tube 43 assembled as described, projects endwise into a cylindrical shell 45 through one end wall 46 thereof, the opposite end of the shell 45 being closed by a plate 47.

The annular space between the tube 43 and the shell 45 provides for the passage of oil to be heated and which enters through an inlet 48 and leaves through an outlet 49. Heat transfer elements 50 are arranged within this annular space, being fixed to the duct 43 in heat transfer relation thereto but clear of the shell 45. These elements 50 are preferably serpentine lengths of heavy wire arranged substantially radially about the duct 43 as shown in Figure 14. By virtue of the curved shape of the elements 50, as viewed in Figure 14, the space between them is substantially uniform throughout their length. This arrangement also facilitates cleaning of the elements which, of course, necessitates withdrawal of the heating assembly by removal of the end wall 46.

We have also devised simple formulae that will enable those fully skilled in the art, and even others less skilled, to determine with reasonable accuracy the borderlines within which the surface conductance (alpha value) of the medium

of lower surface conductance and the total area of the heat transfer elements exposed thereto should lie in order to secure an efficient apparatus of the kind described.

- 5 One of the factors of each of these formulae is the difference between the products of the surface conductance (alpha value) times the area on one side of the wall and the corresponding product on the other side of the wall. This factor is designated Y in the formulae. For each formula we have determined the limits between which the optimum value of this factor Y lies. The surface conductance of the medium having the lower alpha value has been designated α_1 and the heat transfer surface area in contact therewith as A_1 ; and for the medium with the higher surface conductance the corresponding designations are α_2 and A_2 . The product of these latter values divided by the variable factor Y will give the $\alpha_1 \times A_1$ product for the medium of the lower surface conductance, and with the factor Y given if any three of the other factors in the formula

$$25 \quad \alpha_1 \times A_1 = \frac{\alpha_2 \times A_2}{Y}$$

are known the value of the fifth factor can be easily determined.

- 30 Apparatus designed and built according to these formulae while perhaps not perfect will have very high efficiency and small space requirements as contemplated by our invention.

- 35 The more important of these formulae follow: For the convection surfaces of a steam boiler wherein the tubes contain a water and steam emulsion α_2 =approximately 10,000 kg. cal./m.²/°C./h., and the factor Y will vary between 10 and 40 and preferably between 16 and 24.

- 40 For water in motion as in the economizer tubes of a steam boiler, α_2 =approximately 5000 kg. cal./m.²/°C./h., and the factor Y will vary between 10 and 50 and preferably between 20 and 30.

- 45 In such applications of the invention as in the preheating of oil where condensing steam is used as the heat source, α_2 =approximately 10,000 kg. cal./m.²/°C./h., and the factor Y will vary between 8 and 24 and preferably between 10 and 15.

- 55 With the information here given those fully skilled in the art will have little difficulty in determining the actual values applicable in each particular case, and in making corrections necessary to achieve still higher efficiency. For instance, in the case of water in motion, where the approximate alpha value was stated as 5000, if the actual alpha value is found to be 6000, the correct value for the factor Y can be established as follows:

$$60 \quad Y_a = \frac{\alpha_2}{5000} \times Y \text{ (arbitrarily chosen as 20 from range given in formula)}$$

- 65 and substituting—

$$Y_a \text{ (the desired correct) } = \frac{6000}{5000} \times 20 = 24$$

- 70 However, as long as the values of Y lie within the ranges given in the foregoing formulae sufficiently accurate results will be had and apparatus designed in accordance therewith will be far superior to that heretofore available.

In conclusion it should be noted that the vari-

15

ous limits herein prescribed apply to all embodiments of the invention—though not specifically stated in each case, except where such limits are not applicable to a particular embodiment.

This application is a continuation in part of the copending application Serial No. 23,726, filed April 28, 1948, now abandoned.

What we claim as our invention is:

1. A steam boiler having a flue gas passage, boiler fluid conducting tubes within the gas passage and a heat exchanger within the passage and including said tubes characterized by the provision of: heat transfer elements joined to said tubes and collectively forming a heat absorbing screen extending across the entire flue gas passage, said elements being made of high conductivity material and having a substantially uniform cross section throughout their length of between 3 and 50 square millimeters and of a shape wherein the major transverse dimension does not exceed three times the minor transverse dimension, all of said elements being substantially parallel to one another and crosswise to the gas flow through the flue gas passage, and each element being of such length that the heat conductance path afforded thereby to the wall of the tube to which it is joined is not less than ten times the square root of the cross sectional area of the element nor longer than that at which the efficiency of its conductivity as determined by the formula

$$\eta_s = \frac{1}{nl} \times \frac{e^{2nl} - 1}{e^{2nl} + 1} \text{ where } n = \sqrt{\frac{\alpha \times F}{\lambda \times f}}$$

and where

α =the surface conductance (alpha value) of the gases flowing over the elements

λ =the conductance of the elements

e =base natural logarithm ($=2.718$)

F =circumference of element in M

f =cross sectional area of element in M^2

l =length of conductance path in M

is less than seventy-five percent of theoretically complete heat transfer, for situations where the temperature to which the elements are subjected is 600° C. or over and less than sixty percent of theoretically complete heat transfer for temperatures under 600° C., the distribution of said heat transfer elements being substantially uniform across the entire flue gas passage, and the combined surface area of the elements being three to sixteen times as great as the projected area of that length of the tubes on which elements are mounted so that said elements constitute the primary heat exchange surfaces of the heat exchanger in contact with the flue gases.

2. The apparatus defined in claim 1 further characterized by the fact that the length of the heat transfer elements is such that the product of the surface conductance of the flue gases times the total surface area of all of the elements exposed to the flue gases equals the quotient derived from the division, by a factor lying between 16 and 24, of the product of the surface conductance of the boiler fluid times the area of the inside surface of that length of the tubes upon which the elements are mounted.

3. The structure set forth in claim 1 further characterized by the fact that the combined volume of the extended surface provided by said heat transfer elements is between five and twenty-five percent of the total volume of that portion of the flue gas passage containing said elements.

4. The apparatus defined in claim 1 further

16

characterized by the fact that the total surface area of the extended surface provided by the heat transfer elements exposed to the gases is not less than 50 square meters nor more than 200 square meters per cubic meter of that portion of the gas passage containing the elements.

5. Means for effecting heat exchange between two flowing media, comprising: means defining a passage through which one of the media flows; 10 a plurality of ducts arranged in a group within said passage and through which the other medium flows; and heat transfer elements intimately joined to the exterior surface of the ducts and extending therefrom in a direction crosswise of the flow through said passage, said elements having a conductivity of not less than 90 kcal. per hour per square meter per meter thickness per degree centigrade difference in temperature, the junctions of said elements with the ducts being substantially uniformly spaced along the ducts 15 in said group and each of said elements being of approximately round cross section and having a substantially uniform cross section throughout its length of between 3 and 50 square millimeters and the extended portion thereof having a length of not less than ten times the square root of its cross sectional area and not more than that at which the efficiency of its conductivity, as determined by the formula

$$\eta_s = \frac{1}{nl} \times \frac{e^{2nl} - 1}{e^{2nl} + 1} \text{ where } n = \sqrt{\frac{\alpha \times F}{\lambda \times f}}$$

and where

35 α =the surface conductance (alpha value) of the gases flowing over the elements

λ =the conductance of the elements

e =base natural logarithm ($=2.718$)

40 F =circumference of element in M

f =cross sectional area of element in M^2

l =length of conductance path in M

is less than sixty percent of theoretically complete heat transfer.

45 6. The structure set forth in claim 5 further characterized by the fact that the length of the heat transfer elements is such that the product of the surface conductance of the medium flowing through the passage times the total surface area of the extended portions of the elements equals the product of the surface conductance of the medium flowing through the ducts times the area of the inside walls of the ducts in said group, after said latter product is divided by a factor lying between 8 and 40.

7. Means for effecting indirect heat exchange between two media confined to zones separated by a wall through which some heat transfer takes place characterized by the provision of: heat transfer elements intimately joined to said wall in heat transfer relation thereto and extending therefrom, whereby said elements are in direct heat transfer relation with the medium at said side of the wall and in indirect heat transfer relation with the medium at the other side of the wall, said elements being made of material having a conductivity of not less than 90 kcal. per hour per square meter per meter thickness per degree centigrade difference in temperature

70 and the extended portion of each of said heat transfer elements having an approximately round and substantially uniform cross section throughout its length of between 3 and 50 square millimeters and having a length of not less than ten times the square root of its cross sectional area

and not more than that at which the efficiency of its conductivity as determined by the formula

$$\eta_s = \frac{1}{nl} \times \frac{e^{2\pi l} - 1}{e^{2\pi l} + 1} \text{ where } n = \sqrt{\frac{\alpha \times F}{\lambda \times f}}$$

and where

α =the surface conductance (alpha value) of the gases flowing over the elements

λ =the conductance of the element

e =base natural logarithm ($=2.718$)

F =circumference of element in M

f =cross sectional area of element in M^2

l =length of conductance path in M

is less than sixty percent of theoretically complete heat transfer, said elements being substantially uniformly spaced over the wall and their junctions to the wall being spaced from one another in all directions, the combined area of all of the junctions measured at the surface of the wall being at least ten percent of the total area of the wall, the combined volume of the extended portions of said elements being between five and twenty-five percent of the volume of the zone in which they lie and the length thereof being such that the product of the surface conductance of the medium in direct contact with said elements times the total surface area of the extended portions of the elements equals the product of the surface conductance of the other medium times the area of the heat exchange surface exposed thereto after said latter product is divided by a factor lying between 10 and 30.

8. A heat exchange unit for use in steam boilers and the like, comprising: a pair of spaced substantially parallel water-conducting tubes; and heat transfer elements mounted on and connecting said tubes, said elements comprising a series of elongated wire loops embracing and in contact with both tubes and spaced apart along the length thereof, alternate ones of the loop sides at both sides of the median plane containing the axes of the tubes and the major axis of each loop being substantially straight between their points of tangency with the curved surfaces of the tubes, the remaining loop sides having their portions in contact with the tubes wrapped partially around the curved surfaces of the tubes and being spaced inwardly of said first designated loop sides and substantially parallel thereto, the extent of said inward disposition of the second designated loop sides being such as to substantially equally divide the center-to-center distance between the first designated loop sides measured at right angles to said median plane; and means securing the loops to the tubes in intimate good heat exchange relation thereto.

9. The structure set forth in claim 8 further characterized by the fact that the wire of which said loops are formed has a substantially round cross section with a cross sectional area of between 3 and 50 square millimeters and a conductivity of at least 90 kcal. per hour per square meter per meter thickness per degree centigrade difference in temperature.

10. A heat exchanger comprising: means defining two adjacent fluid passages separated by a common wall; and a multiplicity of heat transfer elements joined to said wall in intimate heat transfer relation thereto and extending therefrom into and substantially entirely across the passage at that side of the wall, all of said heat transfer elements being of substantially the same uniform cross section of between 3 and 50 square

millimeters throughout their lengths and of such cross sectional shape that the major transverse dimension does not exceed three times the minor transverse dimension, and said elements providing heat conductivity paths each of which is of a length not less than ten times the square root of the cross sectional area of the elements nor longer than that at which the efficiency of its conductivity as determined by the formula

$$\eta_s = \frac{1}{nl} \times \frac{e^{2\pi l} - 1}{e^{2\pi l} + 1} \text{ where } n = \sqrt{\frac{\alpha \times F}{\lambda \times f}}$$

and where

α =the surface conductance (alpha value) of the gases flowing over the elements

λ =the conductance of the element

e =base natural logarithm ($=2.718$)

F =circumference of element in M

f =cross sectional area of element in M^2

l =length of conductance path in M

is less than sixty percent of theoretically complete heat transfer, and said heat transfer elements being substantially equispaced from one another throughout their lengths and uniformly distributed crosswise of the passage in which they are located, and the combined surface area of said elements being three to sixteen times greater than the projected area of that part of the wall to which they are attached.

11. A steam boiler having a flue gas passage, boiler fluid conducting tubes within the gas passage and a heat exchanger within the gas passage, and including said tubes, characterized by the provision of: wire-like heat transfer elements of high conductivity metal joined to the tubes in intimate heat exchange relation thereto and extending therefrom with all of the elements crosswise to the gas flow and substantially uniformly spaced from one another throughout their lengths and also uniformly distributed across the flue gas passage, all of said elements having a substantially uniform cross section throughout their lengths of between 3 and 50 square millimeters and the length of the extended portion of each element being such that the conductance path afforded thereby to the wall of the tube to which said path leads is not less than ten times the square root of its cross sectional area, nor longer than that at which the efficiency of its conductivity as determined by the formula

$$\eta_s = \frac{1}{nl} \times \frac{e^{2\pi l} - 1}{e^{2\pi l} + 1} \text{ where } n = \sqrt{\frac{\alpha \times F}{\lambda \times f}}$$

and where

α =the surface conductance (alpha value) of the gases flowing over the elements

λ =the conductance of the element

e =base natural logarithm ($=2.718$)

F =circumference of element in M

f =cross sectional area of element in M^2

l =length of conductance path in M

is less than sixty percent (60%) of theoretically complete heat transfer, and the combined surface area of the extended portions of all of said elements being between 3 and 16 times greater than the projected area of that length of the tubes on which elements are mounted so that said heat transfer elements constitute the primary heat exchange surfaces of the heat exchanger in contact with the flue gases.

12. The steam boiler defined in claim 11 further characterized by the fact that each of said heat

transfer elements is substantially round in cross section.

13. A steam boiler having a flue gas passage, boiler fluid conducting tubes within the gas passage and a heat exchanger within the gas passage, and including said tubes, characterized by the provision of: wire-like heat transfer elements of high conductivity metal joined to the tubes in intimate heat exchange relation thereto and extending therefrom with all of the elements cross wise to the gas flow and substantially uniformly spaced from one another throughout their lengths and also uniformly distributed across the flue gas passage, all of said elements having a substantially uniform cross section throughout their lengths of between 3 and 50 square millimeters and the length of the extended portion of each element being such that the conductance path afforded thereby to the wall of the tube to which said path leads is not less than ten times the square root of its cross sectional area, nor longer than that at which the efficiency of its conductivity as determined by the formula

$$\eta_s = \frac{1}{nl} \times \frac{e^{2nl} - 1}{e^{2nl} + 1} \text{ where } n = \sqrt{\frac{\alpha \times F}{\lambda \times f}}$$

and where

α =the surface conductance (alpha value) of the gases flowing over the elements

λ =the conductance of the element

e =base natural logarithm ($=2.718$)

F =circumference of element in M

f =cross sectional area of element in M^2

l =length of conductance path in M

is less than sixty percent (60%) of theoretically complete heat transfer, the combined surface area of the extended portions of all of said elements being between 3 and 16 times greater than the projected area of that length of the tubes on which elements are mounted so that said heat transfer elements constitute the primary heat exchange surface of the heat exchanger in contact with the flue gases, and the length of the heat transfer elements being such that the product of the surface conductance of the flue gases times the total surface area of all of the elements exposed to the flue gases equals the quotient derived from the division, by a factor lying between 16 and 24, of the product of the surface conductance of the boiler fluid times the area of the inside surface of that length of the tubes upon which the elements are mounted.

Certificate of Correction

Patent No. 2,469,635.

May 10, 1949.

DAVID DALIN ET AL.

It is hereby certified that errors appear in the printed specification of the above numbered patent requiring correction as follows:

Column 3, line 73, after the word "considering" insert *the*; column 7, line 18, before the number "963" insert a decimal point; line 25, for "temperature" read *temperatures*; line 33, for "than" read *that*; column 8, line 28, for "50 mm.²" read *50 m.²*; line 29, for "200 mm.²" read *200 m.²*; column 11, line 40, before "used" insert *that*; column 12, line 28, for "maintenance and" read *maintenance of*; and that the said Letters Patent should be read with these corrections therein that the same may conform to the record of the case in the Patent Office.

Signed and sealed this 18th day of October, A. D. 1949.

[SEAL]

THOMAS F. MURPHY,
Assistant Commissioner of Patents.
